(57) CLAIM

The ornamental design for a bracelet, as shown and described.

DESCRIPTION

FIG. 1 is a top, front, left side perspective view; FIG. 2 is a top plan view;

FIG. 3 is a bottom plan view;

FIG. 4 is a front elevation view;

FIG. 5 is a left side elevation view; and,

FIG. 6 is a right side elevation view.

The broken lines shown in the drawings represent portions of the bracelet which form no part of the claimed design.
